(57) **CLAIM**

We claim the ornamental design for a pendant, as shown and described.

DESCRIPTION

FIG. 1 is a top perspective view of a pendant showing our new design;

FIG. 2 is a bottom perspective view thereof FIG. 1;

FIG. 3 is a front elevational view thereof FIG. 1;

FIG. 4 is a rear elevational view thereof FIG. 1;

FIG. 5 is a left side elevational view thereof FIG. 1;

FIG. 6 is a right side elevational view thereof FIG. 1;

FIG. 7 is a top plan view thereof FIG. 1; and

FIG. 8 is a bottom plan view thereof FIG. 1.

FIG. 9 is a top perspective view of second embodiment showing our new design;

FIG. 10 is a bottom perspective view thereof FIG. 9;

FIG. 11 is a front elevational view thereof FIG. 9;

FIG. 12 is a rear elevational view thereof FIG. 9;

FIG. 13 is a left side elevational view thereof FIG. 9;

FIG. 14 is a right side elevational view thereof FIG. 9;

FIG. 15 is a top plan view thereof FIG. 9; and,

FIG. 16 is a bottom plan view thereof FIG. 9.

The broken lines shown in the drawings are included for the purpose of illustrating elements of the pendant that form no part of the claimed design.
